Des. 203,556
Patented Jan. 25, 1966

203,556

SPRAY CAN DEACTIVATOR

Roy L. White, Hutchinson County, Tex.
(8 Sands St., Phillips, Tex.)

Filed Apr. 20, 1965, Ser. No. 84,883

Term of patent 14 years

(Cl. D54—13)

FIG. 1

FIG.2

FIG.4

FIG.3

FIGURE 1 is a top front oblique perspective view of a spray can deactivate showing my new design;

FIGURE 2 is a top view thereof;

FIGURE 3 is a top view of the deactivate with the top cap thereof removed to show the interior;

FIGURE 4 is a front elevation view.

I claim:

The ornamental design for a spray can deactivate, as shown.
